INVENTOR

Anton V. Knoll.

UNITED STATES PATENT OFFICE.

ANTON V. KNOLL, OF DAVENPORT, IOWA.

DRAINAGE-VALVE.

No. 882,784.

Specification of Letters Patent. Patented March 24, 1908.

Application filed May 18, 1906. Serial No. 317,443.

To all whom it may concern:

Be it known that I, ANTON V. KNOLL, of Davenport, in the county of Scott and State of Iowa, have invented new and useful Improvements in Drainage-Valves, of which the following is a specification.

This invention relates to the class of faucets or drainage valves which have the delivery at the end of the faucet-barrel, and it 10 consists in an improved construction and combination of the component parts of said faucet, whereby the same is rendered durable and self adjusting to maintain it perfect in its operation, and which also admits of 15 readily connecting the gate to the barrel of the faucet, and of as readily removing said gate when required for repairs or renewal, all as hereinafter more fully described, and specifically set forth in the claims.

20 The invention is fully illustrated in the annexed drawings, in which

Figure 1 is a perspective view of my improved faucet, showing it in its closed position. Fig. 2 is a longitudinal section of the 25 same. Fig. 3 is a detail view of the gate. Fig. 4 is a detail view of the clamp, and Fig. 5 is a bottom view of the discharge end of the faucet in its closed position.

Similar letters of reference indicate corresponding parts.

A represents the barrel of the faucet, usually formed with a downward deflection at its discharge end. The barrel is provided with trunnions B on opposite sides. On 35 these trunnions is hung or pivoted the clamp C, consisting of arms, pivoted as aforesaid on opposite sides of the barrel, and reaching across the front or face of the barrel, where they are provided with a forwardly extending set screw D, by which to secure the gate in its closed position. The gate L is hingedly connected to the top of the barrel at H, and on the front portion of said gate is interposed a valve or gasket M, which is removably connected to the gate L, by means of the stem or stud N projecting from the tip F of the gate L, as shown in Fig. 2 of the drawings. A portion of the rim of the gate L is cut away at O, to bring this part of the gate 45 flush with the discharge end of the barrel. Oppositely disposed lugs P on the gate prevent the clamp C from passing downwardly beyond the middle point of the gate when in a closed position. A seat S is provided at the 50 inlet end of the barrel for the reception of a gasket and the faucet or drainage valve may

be attached to a vessel by screws passing through a plurality of apertures R in the flange T at the inlet end of said barrel. A seat V is provided at the extremity of the tip 60 F on the gate L, for the reception of the distal end of the set screw D.

I am aware that prior to my invention gates or valves have been trunnioned at opposite sides of the faucet barrel and arranged 65 to slide over the discharge end thereof, also that gate provided with a swinging frame pivotally attached to the upper side of the barrel have been in use. They have in most instances, been adapted to slide against a 70 plane or segmentally curved face on the faucet barrel, and in all such cases the tightness of the valve or faucet is contingent upon the smoothness of said face. In my invention, I have obviated the necessity for a perfectly fitted valve or for the correction of the 75 wear incident to a sliding connection and my valve can be instantly opened or closed.

Having thus fully described my invention, what I claim as new, and desire to secure by 80 Letters Patent is—

1. The combination with a faucet-barrel provided with a plane face a hinged gate fitted against said face, an open frame trunnioned on opposite sides of the barrel straddling the front part of the barrel, a set screw in the frame pressing the gate against the face of the barrel, shoulders on gate adapted to arrest the descent of the frame when the gate shall be fully closed, substantially as set forth. 85 90

2. The combination with a faucet-barrel provided with a plane face a hinged gate fitted against said face, a clamp trunnioned on opposite sides of the barrel and extending across the face of the barrel, a forwardly extending set screw in the clamp adapted to press the gate against the face of the barrel, a metallic tip on the gate adapted to engagement with the set screw, shoulders on the gate adapted to arrest the descent of the 100 clamp, substantially as described. 95

3. The combination with a faucet-barrel provided with a plane face, a hinged gate fitted against said face, a clamp trunnioned on opposite sides of the barrel and extending 105 across the face of the barrel when the valve is in a closed position, a set screw in the front of the clamp, a raised metallic tip centrally disposed on the outer surface of the gate and adapted to receive the set screw, shoulders 110 on the gate adapted to arrest the descent of the clamp, a gasket interposed on the inner

portion of the gate, a stem adapted to connect the gasket to the gate, a gasket seat at the inlet end of the barrel, a flange provided with a plurality of apertures adapted to secure the faucet to a vessel, substantially as described.

In testimony whereof I have signed my

name to this specification in the presence of two witnesses.

ANTON V. KNOLL.
